UNITED STATES PATENT OFFICE.

EDWARD R. KAST, OF PEARL RIVER, NEW YORK, ASSIGNOR TO KAST INSETTING AND GATHERING MACHINE CO., OF NEW YORK, N. Y., A CORPORATION OF DELAWARE.

CONVEYER CHAIN.

Application filed December 28, 1922. Serial No. 609,478.

The present invention is an improvement in the mechanism for conveying groups of signatures to a stitching device or other instrumentality, and particularly is an improvement in the pusher member that engages the rear edges of the signatures of the successive groups.

These pusher members are carried by the endless conveyer that progresses the groups of signatures from the point where they are deposited on the conveyer to the support on which they are stitched or otherwise operated upon. At the point where the groups of signatures pass onto the support on which they are stitched, the endless conveyer passes around a sprocket wheel and its direction of travel passes from the horizontal to the vertical. This is the point at which jamming usually takes place; that is to say, it frequently happens that for one reason or another a group of signatures will be stopped at this point while the conveyer carrying the pusher members will continue to move. In the constructions heretofore employed, the pusher pins have frequently been broken off under these conditions, the links of the conveyer have been wrenched out of alignment, and even the sprocket wheel over which the conveyer chain passes at this point has been injured. Jams of this kind accordingly have been productive not only in loss of time while the difficulty is being attended to, but also in injury to the device.

The object of the present invention is to provide a pusher member which will firmly engage the rear edges of the signatures of a group and operate in the normal functioning of the parts with all of the effectiveness of a rigid pusher member and yet which will, in the event of a jam, yield and pass under the jammed signature group, thus protecting the device from injury and minimizing the seriousness of such an occasion and the time which is necessary to remove the jammed signature group and permit the machine to function normally.

The invention will be better understood by reference to the accompanying drawings illustrating one expression of the inventive idea, and wherein—

Fig. 1 is a side elevation showing a conveyer equipped with improved pusher members and also the parts of the apparatus where jams usually occur;

Fig. 2 is a perspective view of a con-

veyer equipped with the improved pusher member;

Fig. 3 is a cross-section; and

Fig. 4 is a side elevation of the pusher member.

Referring to the drawings, wherein like reference numerals indicate like parts, 5 indicates a support such as is customarily used on "stitcher feeders" and on which the groups of signatures are placed and from 65 which they are removed to an endless conveyer 6 by a pusher member 7. This endless conveyer is usually constituted by a plurality of saddle-shaped links which are connected together in any suitable manner and 70 which pass around a sprocket wheel 8 mounted at 9 in a standard 10. The conveyer 6 is mounted on any suitable support 11 and the signatures are progressed by said 75 conveyer from the dotted line position A on the standard 5 to the dotted line position B on the main saddle or support 12. In Fig. 1 the conveyer is shown passing around the sprocket wheel 8 and at the point where it changes from its horizontal to its vertical 80 traverse. It is at this point that the jams occur for the most part, and where the damage occurs by reason of the unyielding pusher, as heretofore employed, continuing to move and press against the group of signatures that has been stopped for one reason or 85 another.

The pusher member illustrated herein is normally unyielding and yet, in the event of a jam, it yields in the line of travel of said 90 conveyer and passes under the jammed group, thus protecting the parts from injury and minimizing the damage to the group of signatures and the time necessary to clear 95 away the obstacle. As illustrated, this pusher consists of a base portion 13 that is secured to the conveyer 6 in any desired manner. Preferably, this base portion is provided with a downwardly projecting hooked portion 14 that projects between meeting 100 edges of two of the links and is held in place by the forward edge of one link engaging in the recess 15. This base piece may be fixedly secured in position on the inclined side 105 of the link by a screw or other means passing through the horizontal portion thereof. Mounted on this base portion 13 is the pusher member or pin 16 which is pivoted to the base portion at 17 and projects from the inclined side of the link on which the base 110

piece or portion 13 is mounted. A spring 18 is coiled about this pivot 17 and one end 19 of said spring bears against a pin 20 carried by the pusher 16. The other end of said 5 spring bears against a pin 21 carried by the base 13. As shown in Figs. 2 and 3, two of these pusher members are preferably mounted in the same transverse plane passing through the conveyer.

10 There is thus provided a simple and highly efficient pusher member which is readily secured in position on the conveyer 6 and which functions perfectly under all normal conditions and yields in the event of a jam, 15 thus protecting the device. The simplicity of the pusher renders it possible to manufacture the same very cheaply and quickly and also to place it in position or removing it from the conveyer expeditiously and 20 simply.

While, for the purpose of illustration, one expression of the inventive idea has been illustrated and described, it is to be understood that the invention is not limited thereto, and that the inventive idea may be embodied in various mechanical expressions 25 within the limits of the appended claims.

What is claimed is:—

30 1. A signature conveyer comprising a single chain of interconnected links, a separate base piece carried by one of said links, a pusher pin mounted on said base piece and adapted to engage the rear edges of the signatures, and a pivotal connection between the base piece and said pusher pins.

40 2. A signature conveyer comprising a single endless chain of interconnected links, a separate base piece carried by one of said links, a pusher pin pivotally mounted on said base piece and adapted to engage the rear edges of the signatures, and a spring interposed between the base piece and said pusher pin.

45 3. A signature conveyer comprising a single endless chain of interconnected links and a plurality of devices spaced along said chain, each of said devices consisting of a base piece detachably connected with a conveyer link, a pusher pin pivotally mounted on said base piece and adapted to engage the rear edges of the signatures and a spring interposed between the base piece and said pusher pin.

50 55 4. In a signature conveyer, the combination of a plurality of interconnected links for supporting the signatures, and a device provided with a hook portion extending between a pair of said links and engaged under one of the latter and a pusher pin for engaging the rear edges of the signatures.

60 65 5. In a signature conveyer, the combination of means for supporting the signatures including a link element and a device provided with a hook portion fitted on one extremity of said link element and a yield-

ably mounted pusher pin for engaging the rear edges of the signatures.

6. A signature pushing device provided with a hook portion adapted to be fitted on one extremity of a conveyer link and a 70 pusher member for engaging the signatures.

7. A signature pushing device provided with a hook portion adapted to be fitted on one extremity of a conveyer link and a yieldably mounted pusher member for engaging 75 the signatures.

8. In a signature conveyer, the combination of a plurality of links connected together and on which the signatures are supported, a base piece detachably mounted on 80 one of said links and engaged under an edge portion thereof, and a pusher resiliently mounted on said base piece and normally engaging the rear edges of the signatures but adapted to yield in their path of travel. 85

9. In a signature conveyer, the combination of a plurality of saddle-shaped links connected together and on which the signatures are supported, a base piece extending from one of said links and detachably secured thereto, and a pusher member resiliently and pivotally mounted on said base piece and normally engaging the rear edges of the signatures but adapted to yield in their path of travel. 90

10. In a signature conveyer, the combination of a plurality of saddle-shaped links connected together and on which the signatures are supported, a base piece detachably mounted on an inclined side of one of said links and engaged under an edge portion thereof, a pusher member normally engaging the rear edges of the signatures but adapted to yield in their path of travel, and a resilient pivotal connection between the 105 pusher member and said base piece.

11. In a signature conveyer, the combination of a plurality of saddle-shaped links connected together and on which the signatures are supported, a base plate detachably secured on an inclined side of one of said links, a pusher member pivotally mounted on the base plate and normally engaging the rear edges of the signatures but adapted to yield in their path of travel, and a spring 110 interposed between the pusher member and said base plate.

12. In a signature conveyer, the combination of means for supporting the signatures including a link element, a base plate 120 mounted on the link element and having a projecting part provided with a recess receiving an edge portion of said link element, and a pusher member mounted on the base plate for normally engaging the rear edges 125 of the signatures and adapted to yield in their path of travel.

13. In a signature conveyer, the combination of a plurality of saddle-shaped links connected together and on which the signa- 130

tures are supported, a base plate mounted on an inclined side of one of the links and having a projecting part provided with a recess receiving an edge portion of said link, 5 a pusher member mounted on the base plate and normally engaging the rear edges of the signatures, and a connection between the base plate and pusher member providing for yielding movement of the latter in the path 10 of travel of the signatures.

14. A signature pushing device comprising a base provided with a projection having a recess therein adapted to receive an edge portion of a conveyer link, and a 15 pusher member mounted on the base for movement toward and away from the same.

15. A signature pushing device compris-

ing a base provided adjacent one extremity thereof with a projecting recessed part constituting means for detachably securing the 20 device on a conveyer link, and a pusher member yieldably mounted on said base for movement toward and away from the same.

16. A signature pushing device comprising a base provided with a projecting recessed part constituting means for detachably securing the device on a conveyer link, 25 a pusher member pivotally mounted on the base, and a spring interposed between the base and said pusher member.

In testimony whereof I have signed this specification.

EDWARD R. KAST.
